UNITED STATES PATENT OFFICE.

EDMUND M. BENDHEIM, OF NEW YORK, N. Y.

APPARATUS FOR REPAIRING MOTION-PICTURE FILMS.

1,195,175.

Specification of Letters Patent. Patented Aug. 22, 1916.

Application filed March 3, 1916. Serial No. 81,775.

To all whom it may concern:

Be it known that I, EDMUND M. BENDHEIM, a citizen of the United States, and a resident of New York city, in the county and State 5 of New York, have invented certain new and useful Improvements in Apparatus for Repairing Motion-Picture Films, of which the following is a specification.

This invention relates to an apparatus of 10 novel construction for repairing motion picture films by cutting out the mutilated portion of the film, juxtaposing the ends of the severed sections, and cementing such ends to each other. The apparatus can be readily 15 manipulated, and insures such a correct connection between the film sections, that the apertures of the entire length of the restored film will register truly with the pins of the camera film feeding device.

20 In the accompanying drawing: Figure 1 is a plan of a film repairing apparatus embodying my invention, with the clamps and cutter head thrown back. Fig. 2, a plan showing the cutter head thrown back and the clamp closed. Fig. 3 is a longitudinal section on line 3—3 Fig. 2; Fig. 4, a cross section on line 4—4 Fig. 3; Fig. 5, a cross section on line 5—5 Fig. 3; Fig. 6, a cross section on line 6—6 Fig. 3; Fig. 7 shows a 25 portion of the film after being cut; Fig. 8 shows a portion of the film with the severed piece removed, and the flap scraped, and Fig. 9, shows the film after being repaired.

The apparatus comprises essentially, a 30 fixed table or base plate 1 shown to be mounted on a depending rim 2, and adapted to support a portion of a film 3 to be repaired. From preferably the left portion of table 1 there project upwardly, two rows of 35 fixed pins 4 registering with the apertures 5 of film 3, while the right portion of table 1, is provided with two corresponding rows of pins 6, which may either be projected above the surface of the table or sunk below 40 the same. These vertically movable or disappearing pins are secured to a plate 7, arranged below table 1 and turning on a hinge 45 8. The plate may be raised by means of a cam 9, mounted on a shaft 10 which may be 50 turned by a knob 11, so that in this way the

pins 6 are projected upward through corresponding apertures of table 1. When shaft 10 is turned in an opposite direction, plate 7 is lowered by means of a spring 12, so that the pins will be sunk beneath the surface of 55 the table. To one of the longitudinal edges of table 1, there is hinged, a first clamp 13, a cutter head 14, and a second clamp 15, all arranged in proximity to each other, and adapted to be either thrown back, or to be 60 folded over the table. The cutter head 14, which is flanked by the clamps 13, 15 is preferably so constructed, that a true vertical movement will be imparted to the same, during the cutting operation. To this effect, 65 it is shown to be pivoted at one end to a plunger 16 mounted on a spring 17, and guided within a socket 18 of table 1, the movement of the plunger being restricted by a pin and slot 19. At its other end, the cutter head is provided with a plunger 20, fitted 70 within a socket of the cutter head and influenced by a spring 21, the play of the plunger being defined by a pin and slot connection 22. To each face of head 14 is 75 adapted to be attached a cutting blade 23 having preferably outwardly curved ends, and provided with a slot 24 fitting over corresponding studs 25 of head 14, the blade after being fitted in position, being secured 80 to the head by means of a clamp screw 26. It will be seen that when the cutter head is folded over the table 1, and pressure is applied thereto, the head will be forced vertically downward, so that the knives 23 will 85 squarely cut across the film, with a uniform action throughout their length, the knife edges being received within correspondingly shaped grooves 27 of the table.

To the left of cutter head 14, there is pivoted to the table, the clamp 13, which may thus be projected over the innermost of the fixed pins 4. To accommodate these pins, clamp 13 is provided with a pair of transverse bottom grooves 28, while between such 90 grooves there is secured to the bottom of the clamp a felt- or similar pad 29 adapted to bear upon the body of the film. At its upper side clamp 13 is provided with a longitudinal groove 30 adapted for the reception 95 100

of a slide 31, which is movable upon a ball race 32. From slide 31 extends sidewise an arm 33 to which a scraping tool 34 is secured by a set screw 35. Head 14 is so spaced from 5 clamp 13, that tool 34 is adapted to reciprocate across the film, directly beyond the stroke-plane of the left hand cutter 23. The clamp may be locked to the table by means of a suitable catch 36.

- 10 To the right of cutter head 14, there is pivoted to the table, the clamp 15, which may thus be projected over the innermost of the movable pins 6, said clamp being similar to clamp 13, provided with a pair of 15 film receiving transverse bottom grooves 37, a lower pad 38 and a catch 39. To the inner edge of clamp 15, there is hinged at 40, a presser foot 41 which is of such a length, that when swung downward, it will 20 closely approach clamp 13. The presser foot may be forced downward by means of a spring blade 42, pivoted to clamp 15, at 43, and adapted to be swung over presser foot 41 by means of a handle 44.
- 25 The operation is as follows: The clamps 13, 15 and cutter head 14 are swung back, (Fig. 1), pins 6 are raised, and the film to be repaired is so fitted upon the pins, that its mutilated portion faces a pointer 46 30 marked on table 1, within the sweep of cutter head 14. The clamps are thrown across the table and secured by catches 36, 39 to hold the film in place. That portion of the film located between clamp 13 and cutter 35 head 14 is wetted, and the slide 31 is reciprocated so that scraper 34 will remove the emulsion therefrom. The cutter head is swung forward and is depressed, so as to sever the damaged film section which is discarded after the cutter head has been again 40 swung back. Cement is applied to the scraped portion of the film as indicated at 47 Fig. 8. (In order to permit a free movement of the scraper over the rim, the pins 4 are here omitted). Pins 6 are depressed, the right section of the film is advanced to overlie with its left end or rim, the prepared right rim of the left section, while its extreme left apertures will become 45 engaged by the extreme right fixed pins 4. The presser foot 41 is thrown down, and forced against the superposed rims by the spring blade 42 which is swung over the same. When the film sections have become 50 thoroughly united, the clamps are swung up, and the film which has thus been properly repaired is removed.

It will be seen that with my apparatus the film can be repaired in a quick and neat 60 manner, and that in the film thus repaired, the correct spacing between the apertures of the united sections will be maintained, so that the film may subsequently be engaged in proper manner by the feeding mechanism 65 of the camera.

I claim:

1. A film repairing apparatus, comprising a table adapted to support a film, a plurality of pins projecting therefrom and adapted to engage the film apertures, a cutter head hingedly secured to the table, and means for effecting a vertical reciprocative movement of said cutter head across said table.

2. A film repairing apparatus, comprising 75 a table adapted to support a film, a plurality of pins projecting therefrom and adapted to engage the film apertures, a cutter head operably secured to the table, means for effecting a vertical reciprocative movement of said cutter head across said table, and a pair of spaced cutting blades carried by the cutter head, said blades having outwardly curved ends.

3. A film repairing apparatus, comprising 80 a table adapted to support a film, a plurality of pins projecting therefrom and adapted to engage the film apertures, a cutter head operably secured to the table, means for effecting a vertical reciprocative movement of said cutter head across said table, a pair of spaced cutting blades carried by the cutter head, said blades having outwardly curved ends, and a pair of correspondingly shaped grooves in the table, 85 adapted to be engaged by said blades.

4. A film repairing apparatus, comprising a fixed table adapted to support a film, said table being provided with two rows of apertures, a vertically movable member located 100 below the table, two rows of film engaging pins carried by said member and adapted to be projected through said apertures, whereby said film is adapted to be locked to said table, and means for severing the 105 film.

5. A film repairing apparatus comprising a table adapted to support a film, a series of pins projecting therefrom and adapted to engage the film apertures, a clamp adapted 110 to be projected across the table, said clamp being provided with an upper groove, a slide movable within said groove, an arm extending sidewise from the slide, and a scraper secured to said arm.

6. A film repairing apparatus comprising a table adapted to support a film, a pair of spaced clamps hinged thereto, and adapted to be projected across the same, a presser foot hinged to the inner side of one of said 120 clamps, said presser foot being adapted to be swung across the space intermediate the clamps longitudinally of the table, and a cutter head adapted to be projected across the table between the clamps.

7. A film repairing apparatus, comprising a table adapted to support a film, pins on said table, a cutter head, a first spring plunger engaging the table and to which the cutter head is pivoted, and a second 130

spring-plunger carried by the free end of the cutter head.

8. A film repairing apparatus, comprising a table adapted to support a film, pins on said table, some of said pins being vertically reciprocable, a cutter head hinged to the table, a pair of cutting blades carried by

said head, a first clamp hinged to the table at one side of the cutter head, a slide carried by said clamp, a scraper carried by the 10 slide, a second clamp hinged to the table at the other side of the cutter head, and a presser foot carried by said second clamp.

EDMUND M. BENDHEIM.
